APPARATUS FOR SEPARATING FROM A GAS
OR LIQUID MEDIUM SOLID OR LIQUID
PARTICLES

David Dalin, Kristiansborg, Sweden

Application September 18, 1942, Serial No. 458,906
In Sweden February 21, 1941

3 Claims. (Cl. 183—37)

This invention relates to separators of the type designed for the separation of solid and/or liquid particles from a fluid.

One of the objects of this invention is to provide a separator suitable for the extraction of solid or liquid particles from gases and other fluids, which is simple in construction and design and capable of being produced at a comparatively low cost.

The separator of this invention may be classified as a centrifugal separator in that the burdened fluid is caused to flow in a circular or spiraling path so that the entrained particles leave the fluid stream in response to centrifugal action. A generally circular or spiral shaped diffuser housing provides the means for guiding the fluid flow as desired, the burdened fluid entering the diffuser housing through a tangential inlet and the unburdened fluid leaving the housing through an axial outlet in a side wall thereof. The separated particles leave the diffuser housing through a discharge port in the curved peripheral wall of the housing.

With a view toward improving the operation of separators of this type, this invention has as another of its objects the provision of a novel baffle arrangement within the diffuser housing and substantially on the axis thereof, by which more efficient and complete separation of the particles from the fluid is accomplished.

A further object of this invention is to provide a separator of the character described which lends itself readily to dual application, that is, two or more diffuser housings arranged side by side and so connected that a fan operating in one or more of the diffuser housings effects a flow of burdened carrier fluid through all of the diffuser housings with the separation of the particles from the fluid taking place in the first of the series of diffuser housings.

With the above and other objects in view, which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawing illustrates two complete examples of the physical embodiment of the invention constructed according to the best mode so far devised for the practical application of the principles thereof and in which:

Figure 1 is a cross sectional view through a

separator constructed in accordance with this invention, said view being taken on the plane of the line 1—1 in Figure 2;

Figure 2 is a longitudinal sectional view taken 5 through Figure 1 on the plane of the line 2—2; and

Figure 3 is a detail sectional view similar to Figure 1 but illustrating a slightly modified embodiment of this invention.

10 Referring now to the accompanying drawing, the numeral 5 designates generally a diffuser housing which is preferably of spiral formation as shown, but it may be circular. This housing has flat side walls 6 connected by a curved peripheral wall 7 which in the construction illustrated forms a spiral. At its point of largest diameter the diffuser housing has a tangential inlet opening 8. The top of the inlet is defined by a tangential continuation 9 of the peripheral wall 7, while the bottom thereof is formed by a separate wall section 10 which joins with the peripheral wall at its smallest diameter as at 11. Attention is directed to the fact that the inlet port extends across the full width of the diffuser 15 housing, hence extensions of the side walls 6 define the sides of the inlet.

Suitable duct means (not shown) connects the mouth of the inlet port with the source of particle laden fluid to convey the burdened fluid to 20 the diffuser housing.

Two outlet ports 12 and 13 lead from the diffuser housing, the former providing a means of egress for the unburdened fluid and the latter providing a discharge port for the particles. 25 Thus the port 13 is located in the peripheral wall 7, preferably at its lowermost portion so that the particles discharging therefrom may fall directly into a collecting hopper 14. This collecting hopper has an opening 15 in one side wall thereof 30 through which the accumulated particles may be removed.

The specific location of the discharge port 13 may be varied, and through selection of its specific location, different characteristics of the fluid 45 and particles carried thereby may be most advantageously met. This follows from the fact that as the location of the discharge port 13 is moved farther from the inlet port 8, the velocity of the particles decreases.

50 It should also be appreciated that by having a series of discharge ports 13 arranged along the path of the fluid and progressively farther from the inlet port 8, with each port discharging into a separate collecting hopper a classification of 55 the separated particles can be effected as the

heavier particles would naturally be the first to be expelled, with the lighter particles leaving the housing at the farther removed discharge port or ports.

Such multiple arrangement of discharge ports for classification purposes is illustrated in Figure 3 wherein a second discharge port 13' and a second collecting hopper 14' are provided.

The outlet port 12 through which the unburdened air leaves the diffuser housing, being in one of the side walls 6, is substantially at right angles to the inlet port 8. Thus the fluid must make an abrupt change in direction to pass out through the port 12, which, of course, greatly facilitates the separation of the particles carried thereby.

Any suitable means may be employed to cause the burdened fluid to flow through the diffuser housing, as by having either its inlet or outlet connected to a fan or other fluid moving means. In the present instance a fan 16 is provided which is located in a housing 17 similar to the housing 5 and arranged in juxtaposition thereto with the side walls 6 in which the outlet port 12 is located common to both housings. Thus the outlet 12 provides an inlet port for the housing 17, and inasmuch as the two housings are coaxial the port 12 discharges the unburdened fluid into the center of the housing fan 17.

Like the housing 5, the housing 17 is substantially spiral shaped with its outer curved peripheral wall 18 continuing tangentially as at 19 to provide the top of a discharge port 20, the bottom of which is formed by a wall 21 joined to the curved peripheral wall 18 at its smallest diameter.

While the construction thus far described will operate satisfactorily to remove relatively heavy particles, the efficiency of the separator to remove lighter particles is materially enhanced by the provision of a novel baffle arrangement inside the diffuser housing 5. This baffle arrangement comprises a truncated conical baffle 22 encircling the outlet port 12. This baffle may be an integral part of the adjacent side wall 6 or it may be a separate piece secured thereto. In any event its largest diameter joins with the adjacent side wall 6 and its smallest diameter defines the mouth of the discharge port 12 and has another inner and oppositely directed truncated conical wall 23 joined thereto. The free edge of this latter wall 23 defines the terminus of the discharge port 12 and, as will be readily apparent, is so positioned as to direct the fluid flowing through the port 12 toward the center of the fan 16.

The baffle wall 22, being directed toward the interior of the diffuser housing, deflects particles in the carrier fluid that may be moving toward the outlet port 12 and throws them out toward the peripheral wall 7. In this function the baffle wall 22 is aided by an inwardly directed axially disposed conical protrusion 24 on the opposite side wall 6. Like the truncated conical baffle 22, the protrusion 24 may be formed as an integral part of the adjacent side wall 6 to which it is attached, or it may be a separate unit secured thereto.

From the foregoing description, taken in connection with the accompanying drawing, it will be readily apparent to those skilled in the art that while the specific construction illustrated is adapted for the separation and extraction of solid or liquid particles from a gaseous carrier fluid, the invention is readily susceptible for use in the extraction of solid particles from liquid car-

rier fluids. It will also be apparent that the invention provides a separator of simple and inexpensive construction, and that by virtue of the novel baffle arrangement employed, increased efficiency in the separation of fine particles is obtained.

What I claim as my invention is:

1. A centrifugal separator for unburdening a carrier fluid of particles suspended therein comprising: a diffuser housing of substantially circular formation having substantially flat side walls connected by a substantially circular peripheral wall; means defining a tangential inlet into the diffuser housing; an outlet port in said peripheral wall remote from the inlet through which particles separated from the carrier fluid are expelled; one of the side walls having an outlet opening for the unburdened carrier fluid disposed substantially on the axis of the housing; means for inducing a flow of the carrier fluid through the housing; an inwardly protruding truncated conical baffle encircling the periphery of the outlet opening with the largest diameter thereof adjacent to the side wall in which the outlet is located and its smallest diameter defining the edge of the outlet opening to deflect particles in suspension in the carrier fluid away from said outlet opening; and an inward conical protrusion on the opposite side wall substantially coaxial with the outlet opening with the largest diameter of the conical protrusion adjacent to said opposite side wall and its apex extending a substantial distance in toward the mouth of the outlet opening whereby said baffle and said inward conical protrusion cooperate to deflect any particles still suspended in the carrier fluid outwardly toward the peripheral wall.

2. A centrifugal separator for unburdening a carrier fluid of particles suspended therein comprising: two substantially spiral housings disposed side by side with a common side wall therebetween and with their spirals coaxial; said common side wall having an opening substantially coaxial with the spirals; each of said housings having a tangential port, the ports of the two housings facing in opposite directions and the port of one constituting an inlet for the burdened carrier fluid while the port of the other constitutes an outlet for unburdened carrier fluid; a fan in the latter designated housing designed to draw the carrier fluid into the tangential inlet port in the other housing and through the opening in the common side wall; an inward truncated conical protrusion extending into said other housing from the common side wall substantially on the axis of the spirals with the largest diameter adjacent to the common side walls and its smallest diameter defining the edge of the outlet in the common side wall; and a conical protrusion extending into the same said other housing substantially on the axis of the spirals with the apex thereof pointing toward the outlet in the common side walls; said two protrusions cooperating to deflect particles suspended in said fluid carrier outwardly toward the peripheral wall of the housing into which the protrusions extend; and an outlet port in said outer spiral wall through which such particles are expelled.

3. A centrifugal separator for unburdening a carrier fluid of particles suspended therein comprising: a diffuser housing having substantially flat side walls connected by a substantially circular peripheral wall; means defining a tangential inlet into the diffuser housing; a plurality

of outlet ports in said peripheral wall spaced different distances from the inlet through which particles separated from the carrier fluid are expelled, the heavier particles passing through the outlet port nearest the inlet; separate collecting hoppers to which said outlet ports open, to receive the particles expelled therethrough; one of the side walls of the diffuser housing having an outlet opening for the unburdened carrier fluid disposed substantially on the axis of the housing; means for inducing a flow of the carrier fluid through the housing; an inwardly protruding truncated conical baffle encircling the periphery of the outlet opening with the largest diameter

thereof adjacent to the side wall in which the outlet is located and its smallest diameter defining the edge of the outlet opening; and an inward conical protrusion on the opposite side wall substantially coaxial with the outlet opening with the largest diameter of the conical protrusion adjacent to said opposite side wall and its apex extending a substantial distance in toward the mouth of the outlet opening whereby said baffle and said conical protrusion cooperate to deflect particles suspended in the carrier fluid outwardly toward said peripheral wall in which the outlet ports are located.

DAVID DALIN.
